DESK TRAY

Charles M. Abrahamson, Aurora, Ill., assignor to All-Steel Equipment Inc., Aurora, Ill., a corporation of Illinois

Application January 31, 1956, Serial No. 562,400

1 Claim. (Cl. 211—126)

My invention relates to a desk tray, and more particularly to the type of tray which may be stacked in tiers for receiving correspondence, drawings, and other like papers or objects.

It is often difficult with conventional desk trays to insert and remove papers because of the interference from the interconnecting elements between the stacked trays and also because the lower tray frequently does not provide proper clearance for grasping the papers which are to be removed from that tray.

Furthermore, conventional desk trays are often provided with legs that are prone to scratch the surface of the desk or table upon which they are placed, and when rubber feet are used on the legs the rubber as it ages will often stain the finished tops of the desks or tables. If the bottom of the tray rests directly upon the supporting surface, sharp corners on the tray may also damage the desk or table top.

The principal object of this invention is to provide a desk tray that may be used singly or may be stacked in tiers, and yet overcomes the difficulties mentioned above. The interconnecting elements are located rearwardly of the trays so that they do not interfere with the insertion and removal of papers; and the bottom tray is given ample hand clearance so that there is no difficulty in grasping papers in that tray and removing them. This is accomplished by having the front end of the tray substantially raised above the plane of the base and providing a suitable cut-out for the hand to grip the papers.

Another object of the invention is to provide a tray which has a broad base support so that it is highly resistant to tipping.

It is also characterized by elimination of rubber feet or sharp metal surfaces which could mar or stain the surface upon which it is placed.

Still another object of the invention is to provide a desk tray construction that permits a number of the trays to be united in a stack or tier without reducing the hand clearance to each tray.

Yet another object of the invention is to provide a self-cleaning desk tray.

Other objects, uses, and advantages will be obvious or become apparent from a consideration of the following description and drawings.

In the drawings:

Figure 1 is a front elevational view of a number of trays embodying my invention, arranged in a stack or tier;

Figure 2 is a cross sectional view along line 2—2 of Figure 1;

Figure 3 is a fragmental plan view of a rear corner of one of the desk trays shown in Figures 1 and 2;

Figure 4 is a fragmental side elevational view of the rear end of one of my improved desk trays;

Figure 5 is a front elevational view of one of the supports employed in my improved desk tray, parts being broken away;

Figure 6 is a perspective view of the stack of desk trays

2

shown in Figures 1 and 2, with an additional desk tray shown in phantom;

Figure 7 is a fragmental cross sectional view along line 7—7 of Figure 6;

5 Figure 8 is a plan view of one of my improved desk trays;

Figure 9 is a cross sectional view along line 9—9 of Figure 6; and

Figure 10 is a fragmental plan view illustrating a pin or rod and index card holder that is incorporated in my improved desk tray.

Reference numeral 10 of Figures 1, 2 and 6 indicates a stack or tier of desk trays made up of a plurality of desk trays 12 embodying my invention. As seen more particularly in Figures 1, 2 and 6, each desk tray 12 comprises a J-shaped channel support or base 14 positioned on either side of a relatively flat, rearwardly inclined floor or bottom 16. The floor or bottom 16 merges into an upstanding rear wall 18. The floor or bottom 16 is inclined rearwardly so that papers 19 that are dropped into the trays 12 will tend to slide toward the rear wall 18, as indicated in Figure 2.

The floor 16 merges into the upper ends of the shorter legs 20 of the respective channel or trough supports 14, and the upper ends or edges of these shorter legs 20 and floor 16 incline downwardly rearwardly of the desk tray. The shorter legs 20 of each support 14 merge into webs 22 that in turn merge into relatively long legs 24 (of channel supports 14) that form the side walls of the desk tray. As seen in Figure 8, the front edge of the floor or bottom 16 is concavely cut out as at 26 to permit one to readily grasp papers and the like resting on the floor or bottom 16, particularly the bottom tray when resting on a desk, table, or other such flat surface.

35 In the illustrated and preferred embodiment, I prefer to form the desk trays 12 out of a single sheet of relatively inflexible material such as common types of sheet metal. The sheet metal is formed by any suitable operation to indent the floor or bottom 16 above the webs 22 and bend the longer legs 24 of J-shaped supports 14 and the appendage forming rear wall 18 to the illustrated upright positions. As shown in Figures 2 and 3, preferably the edges of the webs 22 are curved upwardly as at 30 to insure that all sharp or rough edges are directed away from the surfaces on which the desk tray may rest. The trays 12 may be of any desired length and width, for instance, the lower legal size and upper letter size shown in stack 10.

40 As shown in Figures 6 and 8, a relatively flat plate 32 is secured to the outer surface 34 of each longer leg 24 of the supports 14. Each plate 32 is generally quadrilateral in configuration and the vertical edges are curled or bent into a generally semi-cylindrical configuration, as indicated in 36. The curved portions 36 are indented 45 thereacross somewhat as shown at 38 along approximately the horizontal axis of the respective plates 32.

45 As indicated in Figure 10, the central portion 40 of each plate 32 is indented outwardly of the surface 34 of the respective supports 14 and an aperture 42 formed therein. The indented central position 40 forms with the respective legs 24 a pocket 44 adapted to receive index cards 45 or the like.

The curled edges 36 form with the respective longer legs 24 oppositely directed pockets 46 adapted to receive the ends of rods or pins 48 that are employed when the trays 12 are stacked together. The plates 32 may be secured in place in any suitable manner, as by spot welding, as at 50 in Figure 10.

50 The desk trays 12 may be used separately or assembled in stacks 10 in the manner indicated in the drawings. When assembled in stacks 10, rods 48 are inserted in the respective (upper) pockets 46 formed by

each plate 32 of the lowermost tray, and the next tray is positioned above the bottom tray and the tops of the rods 48 inserted in the lower pockets 46 of this next desk tray. Succeeding desk trays are mounted above the lower desk tray in a similar manner.

It will be noted that when the individual desk trays are resting on a surface 55 (see Figure 2), the webs 22 of channel shaped supports 14 form continuous feet that provide support for the tray throughout its entire length and thus gives a tray great stability. Moreover, the front end of floor or bottom 16 of the tray is spaced considerably above the surface 55, thus permitting more than adequate hand clearance space.

When the trays 12 are arranged in stacks or tiers 10, the rods 48 and the positioning of the floors 16 above the webs 22 provide even greater hand clearance.

As papers tend to overlie the webs 22 when placed in the respective desk trays, the air displaced when papers are dropped in place passes out of the tray through each end of each support 14. This tends to clean off the top of the web 22 and thus insures self-cleaning of the desk tray.

As no rubber feet are required for my desk tray, possible staining of the supporting surface is eliminated. The webs 22 are rigidly connected together by the floor or bottom 16 so that displacement of one with respect to the other is avoided. Each web 22 presents a broad support surface so that the bottom tray when resting on a flat surface is highly resistant to inadvertent tipping.

When the trays 12 are stacked they are in direct vertical alignment and thus take up a minimum of desk or table space.

The foregoing description and the drawings are given

merely to explain and illustrate my invention, and the invention is not to be limited thereto, except insofar as the appended claims are so limited since those skilled in the art who have my disclosure before them will be able to make modifications and variations therein without departing from the scope of the invention.

I claim:

A desk tray formed from a single sheet of material and comprising a generally rectangular planar floor portion flanked on opposite sides by side walls or like configuration with a downwardly extending trough member connecting each side wall with the adjacent side margin of said floor portion, the lower surface of said trough members lying in a plane which is oblique with respect to the plane of said floor portion whereby the tray when placed on a flat surface rests uniformly on said trough members with the floor member inclined rearwardly downwardly, and a rear wall rising upwardly from the rear margin of said floor portion, said trough members providing an air escape path as papers are dropped on the tray.
